DISCONNECTING CONTACT

Charles E. Bickham, Pittsburgh, Pa., assignor to
Westinghouse Electric & Manufacturing Com-
pany, East Pittsburgh, Pa., a corporation of
Pennsylvania

Application February 27, 1941, Serial No. 380,827

5 Claims. (Cl. 200—166)

My invention relates, generally, to electric switches and, more particularly, to the contact members of electric switches suitable for separating or disconnecting current carrying members, as, for example, on circuit breakers utilized in metal-clad switchgear.

In metal-clad switchgear of either the vertical lift or the horizontal drawout type for circuits of high ampere capacity, it is desirable that the primary disconnecting contacts be arranged for flat bar mounting in order to make the most efficient use of the limited available space.

An object of my invention, generally stated, is to provide a disconnecting contact which shall be simple and efficient in operation and which may be economically manufactured and installed.

A more specific object of my invention is to provide a disconnecting contact suitable for use with flat bar conductors.

Another object of my invention is to provide for maintaining uniform contact pressure between the contact members of a disconnecting switch.

A further object of my invention is to avoid the use of flexible shunts in a disconnecting switch having a plurality of movable contact fingers.

Other objects of my invention will be explained fully hereinafter or will be apparent to those skilled in the art.

In accordance with my invention, current is conducted between a movable contact and a stationary contact by means of a plurality of bridging members which are movably mounted on the movable contact by means of a mounting plate that has grooves for maintaining the desired spacing between the bridging members. The bridging members are oppositely disposed in pairs, each pair being held in place by a retainer with a flat spring so disposed between each bridging member and its retainer that pressure is applied on the contact surfaces.

For a fuller understanding of the nature and objects of my invention, reference may be had to the following detailed description taken in conjunction with the accompanying drawing, in which:

Figure 1 is a view, in elevation, of a disconnecting contact constructed according to my invention.

Fig. 2 is a view, in section, taken along the line II—II of Fig. 1, and

Fig. 3 is another view, in section, taken along the line III—III of Fig. 2.

Referring to the drawing, the disconnecting

contact shown therein comprises two parts, a movable contact 10 and a stationary contact 11. As shown, the stationary contact is a rectangular conductor suitable for connecting to the bus bars of a switchgear structure (not shown).

The movable contact 10 comprises a plurality of bridging contact fingers 12 for conducting current between a rectangular member 13 and the rectangular member 11. The member 13 may be mounted on a circuit breaker or other electrical apparatus (not shown) which is to be disconnected from the conducting member 11. The bridging contact fingers 12 are movably mounted on the conducting member 13 by means of a mounting plate 14 which is secured to the end of the conducting member 13 by screws 15. The mounting plate 14 is provided with grooves or notches 16 for retaining the contact fingers 12 in spaced relation across the conducting member 13. The contact fingers 12 are provided with notches 17 which cooperate with the mounting plate 14 to limit the longitudinal movement of the contact fingers on the conductor 13.

As shown, the contact fingers 12 are disposed on the conductor 13 in pairs, the members of each pair being on opposite sides of the rectangular conductor 13. The two members of each pair are retained in place by means of a common retainer 18 which is disposed substantially midway between the ends of the fingers. The retainers 18 are provided at each end with a channel 19 for guiding a contact finger 12 and for retaining a flat spring 21 which is disposed between the retainer 18 and the contact finger 12. As shown in Fig. 2, the flat springs 21 are curved and the ends of each spring engage one of the contact fingers 12 to maintain contact pressure between the finger 12 and the conducting members 11 and 13. In this manner, the fingers of each pair are biased toward each other by the action of the springs 21 and the retainer 18.

In order to prevent collapsing of the contact fingers when they are withdrawn from the conductor 11, a floating bar 22 is disposed between the contact fingers. The bar 22 is provided with notches 23 for assisting in maintaining the desired spaced relation between the contact fingers. The fingers 12 are provided with notches 24 for retaining the floating bar 22 in position between the contact fingers.

If it is desired to limit the sidewise movement of the contact fingers, pins 25 may be inserted through elongated openings 26 provided in the retainers 18; in this manner a predetermined amount of misalignment between the conducting

members 11 and 13 may be permitted. However, the permissible amount of misalignment may be governed by the size of the elongated openings 26.

Vertical alignment of the contact fingers 12 is maintained by a pair of plates 27, one of which is secured on top of the conductor 13 by screws 28 and the other of which is secured to the bottom of the conductor 13 by similar screws 28. The pins 25 extending through the plates 27 may be retained in position by cotter keys 29.

From the foregoing description, it is apparent that I have provided a contact assembly having a relatively high ampere capacity, since the use of flexible shunts for conducting the current is entirely avoided and the current is conducted through rigid members. Furthermore, a uniform contact pressure between each of the bridging fingers and the rectangular conductors is maintained, since the fingers of each oppositely disposed pair are provided with individual springs for maintaining the contact pressure. Thus, the use of equalizing members for distributing the contact pressure between the contact fingers is avoided. Also, the use of helical springs, which require more space than flat springs of the type herein disclosed, is avoided.

I do not desire to be restricted to the particular form or arrangement of parts herein shown and described, since it is evident that they may be changed and modified without departing from the spirit and scope of my invention as defined in the appended claims.

I claim as my invention:

1. A disconnecting contact comprising, a conductor, a plurality of pairs of contact fingers disposed on opposite sides of said conductor, a retainer for each pair of oppositely disposed contact fingers, said retainer having channel-shaped ends for receiving the fingers, and resilient means disposed between the fingers and the retainers for biasing the fingers of each pair toward each other.

2. A disconnecting contact comprising, a conductor, a plurality of pairs of contact fingers disposed on opposite sides of said conductor, a re-

tainer for each pair of oppositely disposed contact fingers, and a curved flat spring member disposed between each finger and its retainer in alignment with the finger for biasing the fingers of each pair toward each other, said retainer engaging said spring substantially midway between its ends which engage the finger.

3. A disconnecting contact comprising, a conductor, a plurality of pairs of contact fingers movably mounted on opposite sides of said conductor, means on said conductor for limiting longitudinal movement of said fingers, said means having recesses therein for maintaining the fingers in spaced relation, a retainer for each pair of oppositely disposed contact fingers, said retainer having channel-shaped ends for receiving the fingers, and resilient means disposed in said channels between each finger and its retainer to engage the finger on opposite sides of the retainer for biasing the fingers of each pair toward each other.

4. A disconnecting contact comprising, a conductor, a plurality of pairs of contact fingers movably mounted on opposite sides of said conductor, means on said conductor for limiting longitudinal movement of said fingers, a movable retainer for each pair of oppositely disposed contact fingers, said retainer having channel-shaped ends for receiving the fingers, means for limiting the movement of said retainers, and resilient means disposed in said channels between each finger and its retainer for biasing the fingers of each pair toward each other.

5. A disconnecting contact comprising, a conductor, a plurality of pairs of contact fingers movably mounted on opposite sides of said conductor, means on said conductor for limiting longitudinal movement of said fingers, a movable retainer for each pair of oppositely disposed contact fingers, means for limiting the transverse and the longitudinal movement of said retainers, and a flat spring member disposed between a finger and its retainer in alignment with the finger for biasing the fingers of each pair toward each other.

CHARLES E. BICKHAM.
